MAIL RECEIVER

Filed Jan. 23, 1928

WITNESS:

INVENTOR

BY *Victor J. Evans*

ATTORNEY

UNITED STATES PATENT OFFICE

ZADA LIZZIE FANCHIER, OF WICHITA FALLS, TEXAS

MAIL RECEIVER

Application filed January 23, 1928. Serial No. 246,687.

This invention relates to mail receivers.

The general object of the invention is to provide a mail receiver that is primarily designed for household use and is adapted to be arranged through the wall of a house so that mail can be delivered within the house with the result, damage and loss of the mail by weather elements or from other causes will be eliminated.

10 A further object of the invention is to provide a mail receiver of the character set forth, that is adjustable so that it can be adapted to fit walls of various thicknesses.

15 Another object of the invention is to provide a mail receiver that is simple in construction, inexpensive to manufacture, and efficient in operation and service.

20 This invention also consists in certain other features of construction and in the combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:

30 Figure 1 is a vertical sectional view taken through the mail receiver forming the subject matter of the present invention and showing the same in applied position in a wall.

Figure 2 is a front elevation thereof.

35 Figure 3 is a sectional view taken approximately on line 3—3 of Figure 1, looking in the direction of the arrows.

Figure 4 is a sectional view taken through a slightly modified form of the invention.

40 Figure 5 is a perspective view of the outside closure plate.

45 Referring to the drawings in detail, the letter A indicates a wall of a building or the like and which is provided with an elongated opening arranged at an inclination for the purpose of accommodating the chute of the mail receiver forming the subject matter of the present invention.

50 The chute is made up of a pair of hollow sections elongated in cross section, indicated respectively by the reference numerals 1

and 2. The section 2 is slightly larger than the section 1 for the purpose of telescopically receiving the same as shown, whereby the chute can be adapted to fit walls of various thicknesses as will be apparent. The section 55 1 has integrally formed therewith or secured thereto in any well known manner a plate 3 having arranged therein openings for receiving bolts 5 which are threadedly secured in sleeves 6, and these sleeves also threadedly receive bolts 7 passing through the inner plate 4 of the device for securing the chute in the opening and in its adjusted position.

The outer end of the chute is closed by a door 5' having a reduced free end providing 65 a handle 6' whereby the door may be moved to its open position as shown in dotted lines in Figure 1. The door has extending from its inner end and disposed in opposed relation with respect to each other, ears 7' providing 70 stops for holding the door in its closed position as shown in full lines in Figure 1. The door is mounted for slidable movement through a slot formed in the plate 3 and normally overlies the outer end of the 75 chute by being disposed in contacting engagement with the plate 3.

The inner end of the chute is also provided with a door which is indicated by the reference numeral 8, and this door is hingedly 80 secured to the inner plate 4.

Depending from the inner plate 4 and being secured thereto in a manner to receive mail passed through the chute is a tray 9 that is relatively narrow and deep and which is 85 formed from wire having two of its ends arranged above the tray proper and bent at right angles upon themselves in opposed relation with respect to each other. The said ends are received in openings 10 formed in 90 the inner plate 4 for the purpose of securing the tray in fixed relation with respect to the plate 4.

The outer plate which is indicated by the reference numeral 3 is also provided with a 95 holder for accommodating mail and this means is formed from wire bent upon itself to provide arms 11 having their upper ends bent to be received in openings formed in the plate 3 for supporting the means below 100

the outer end of the chute as best shown in Figures 1 and 2 of the drawings. The arms extend forwardly at their lower ends, thence are disposed inwardly toward each other, and formed with the inwardly bent portions are upright portions 12 disposed in parallelism with the arms 11, and these upright portions 12 are bent rearwardly in a horizontal plane, and are connected with portions which terminate to provide a hook 13. The mail supporting means just described may be utilized for the purpose of receiving papers, magazines or the like and the hook 13 may be adapted for the purpose of accommodating letters and the like to be taken up by the mail carrier.

In Figure 4 I have illustrated a slightly modified form of chute which also includes telescopically mounted sections indicated for distinction by the reference numerals 14 and 15, but it will be noted that the section 14 is provided with blocks having threaded bores to accommodate bolts 16 passing through openings formed in the inner plate 17 of this form for the purpose of securing the telescopically mounted sections in cooperative adjusted position.

The door 5' may have formed in any well known manner thereon the word "Mail", as shown in Figure 5.

From the above description and disclosure of the drawings, it will be obvious that I have provided a mail receiving device, that may be adjusted to fit various sizes of walls, and is adapted to be arranged through the wall so that mail and the like may be delivered directly in a building and thereby eliminate loss and damage to the mail as well as to overcome the inconvenience of going outside of the building to collect mail delivered.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. In a mail receiving means, a holder formed from wire, arms included in said holder, forward portions formed with the lower ends of said arms, portions formed with the forward portions and being disposed toward each other, upright portions formed with the portions disposed toward each other, rearwardly bent portions formed with the upright portions at their upper ends and being disposed in a horizontal plane, portions providing a hook and being formed with the rearwardly bent portions, the hook forming portions being disposed whereby the hook thereof is arranged forwardly of the upright portions, and said arms having their upper

ends bent and received in openings formed in a plate of a mail chute for securing the holder thereto.

2. In a mail receiver, a chute formed from telescopically mounted sections adapted to be arranged in an opening formed in the wall of a building, threaded bolts carried by said sections, and means threadedly receiving said bolts for securing the sections in cooperative adjusted positions with respect to each other.

In testimony whereof I affix my signature.

ZADA LIZZIE FANCHIER.
